ABSTRACT

A system for producing a vibrato signal which varies in frequency in a manner uncorrelated with time in an electronic musical instrument, in which at least two dissonant signals are applied to a control input of each tone generator via a gate circuit, a divider chain and a low-pass filter.

SYSTEM FOR PRODUCING AN APERIODIC VIBRATO SIGNAL

The invention relates to a system for producing a vibrato signal which varies in frequency in a manner uncorrelated with time, in an electronic musical instrument provided with at least one tone generator.

Such a system is described in U.S. Pat. No. 3,267,199, in which the output signal of an organ is shifted in frequency to the ultrasonic range and then is returned to the initial frequency range by means of the same auxiliary oscillator. Before the signal of this auxiliary oscillator is returned, it is passed through a filter which varies the phase as a function of a second signal. The latter signal may be a noise signal or a low-frequency signal, as is usual for a vibrato. It will be appreciated that such a system is comparatively complicated and hence comparatively expensive.

According to the invention, at least one gate circuit is provided having inputs which are connected, as the case may be, through a pulse shaper, to at least two sources of signals which preferably form a discord within an octave, a control input of each tone generator being coupled to an input of one of the gate circuits via at least one divider-by-two chain.

Thus, there will appear at the output of the last divider-by-two chain or divider-by-two chains, a signal which consists of pulses of continuously varying width, which are spaced by intervals which differ from one another in a manner such that the mean pulse duration is one half of the mean period. The combination of the signals applied to the gate circuit is chosen so that the mean period of the signal at the output of the last divider-by-two chain or at the outputs of the last divider-by-two chains correspond to the period of the signals usually employed for the vibrato.

If, in an embodiment of a system according to the invention, each last divider-by-two chain is followed by a low-pass filter having a cut-off frequency of a value between one and four times the reciprocal of the mean period of the signal at the output of the last divider-by-two chain, there will appear at the output of this filter, a low-frequency signal which has the nature of band noise. Applying this signal to a control input of a generator, the frequency of this generator can be varied statistically about its mean value, so that the sound from this generator will assume the nature of a wind instrument, such as a flute, an organ-pipe, etc.

In a further embodiment of a system according to the invention, each of the signals applied to a gate circuit consists of one of the tone signals produced in the instrument.

It will be clear that such a system is simple, because the signals used are produced in the instrument in any case, so that no additional oscillators are required.

A particularly advantageous embodiment of a system according to the invention includes a gate circuit which is connected to the control inputs of all the tone generators via each divider-by-two chain and via the low-pass filter, if provided.

The term "control input of a tone generator" is used in this specification to mean an input to which the application of a signal of varying magnitude results in a frequency variation of the tone generator. This includes, for example, that part of the supply circuit of which the output voltage feeds the generators. The output voltage may be varied by means of the signal from

the gate circuit, so that the frequencies of the generators vary.

Embodiments of the invention will now be described, by way of example, with reference to the accompanying diagrammatic drawings, in which

FIG. 1 is a circuit diagram of a system according to the invention using four gate circuits, and

FIG. 2 is a circuit diagram of a system using one gate circuit.

10 Referring now to FIG. 1, 12 tone generators $G_1 \dots G_{12}$ are each connected to a divider-by-two chain $D_1 \dots D_{12}$ in each of which chains the frequency of the tone of the associated generator is divided by a factor of 2, so that at the outputs of these divider chains, the lower 15 octave tones are available. The system includes four gate circuits $P_1 \dots P_4$ which each have three inputs which each are connected to an output of one of the divider chains $D_1 \dots D_{12}$, if required, i.e. if the signals at the output of the divider are not sufficiently pulse-shaped, through a pulse shaper $I_1 \dots I_{12}$, respectively. In this case out of the divider chains $D_1 \dots D_{12}$ four groups are formed each consisting of three divider chains ($D_1, D_2, D_3; D_4, D_5, D_6; D_7, D_8, D_9; D_{10}, D_{11}, D_{12}$) whereby the tones at the respective outputs of these divider chains form dissonant intervals of a minor second, so that the gate circuit P_1 is connected to the divider chains D_1, D_2 and D_3 , the gate circuit P_2 is connected to the divider chains D_4, D_5 and D_6 , etc.

30 The outputs of the gate circuits $P_1 \dots P_4$ are each connected to a second divider chain $B_1 \dots B_4$ which each comprise at least one divider-by-two stage, with the result that at the output of each of these divider chains $B_1 \dots B_4$ a pulsatory voltage appears, the mean period of which, corresponds to the period of a signal usually employed for producing a vibrato. The output of each of the divider chains $B_1 \dots B_4$ is connected to a low-pass filter $F_1 \dots F_4$, respectively, having a cut-off frequency which is between one and four times the reciprocal of the mean period of the signal at the output of the respective divider chain $B_1 \dots B_4$.

35 Without the provision of this low-pass filter, the pulsatory signal would cause the generator frequency at the output of the respective divider chain $B_1 \dots B_4$, to be aperiodically and abruptly shifted, from the minimum frequency to the maximum frequency, whereas now the integrating nature of the low-pass filter $F_1 \dots F_4$, causes the frequency to vary more gradually.

40 The signal at the output of each filter $F_1 \dots F_4$ is, respectively applied to the control input of one of the four sets of three generators G_1, G_2 and $G_3, \dots G_{10}, G_{11}$ and G_{12} , respectively, so that the frequency of these generators varies in a manner uncorrelated with time.

45 The outputs of the low-pass filters $F_1 \dots F_4$, need not necessarily be connected each to the associated set of generators G_1, G_2 and $G_3, \dots G_{10}, G_{11}$ and G_{12} , but may alternatively be connected to any other set of three generators. As a further alternative, a different number of gate circuits may be used which each have at least two inputs, provided that each generator is connected to an output of a filter.

50 FIG. 2 shows a particularly advantageous circuit arrangement in which only one gate circuit P is used which has 12 inputs which each are connected to one of the outputs of one of the 12 divider chains $D_1 \dots D_4$. The output of the gate circuit P here also is connected to a divider chain B the output of which is connected to a low-pass filter F . The output of the low-pass filter

F is connected to the control inputs of all twelve generators $G_1 \dots G_{12}$.

This circuit arrangement provides highly satisfactory results if the frequencies of the signals applied to the gate circuits lie between 1,000 Hz and 2,000 Hz, and if the divider stages $B_1 \dots B_4$ again divide these frequencies by a factor of, for example, 16.

The cut-off frequency of each of the low-pass filters $F_1 \dots F_4$ has been chosen to be about 15 Hz.

Obviously in instruments provided with a single generator which is tuned to a different frequency by each key, as will be the case in melody instruments, or from the signal of which all the other signals within the octave are derived, the output of the low-pass filter F must be connected to the control input of this one generator only.

The number of signals applied to the gate circuit, the frequency range from which these signals are taken, and the number of divider-by-two chains at the output of each gate circuit, together determine the mean period, the pitch range, and the repetition rate of the vibrato signal.

What is claimed is:

1. A system for producing a vibrato signal which var-

ies in frequency in a manner uncorrelated with time in an electronic musical instrument, comprising:

a gate circuit;
a plurality of pulse shapers connected to said gate circuit at inputs thereof;
a divider stage connected to said gate circuit at an output thereof;
a plurality of tone generators each having a control input;
a low pass filter connected between the divider stage and each control input of said tone generators; and divider chains connected between said tone generators and said pulse shapers.

2. The system of claim 1, wherein said low pass filter is connected to a set of three generators.

3. The system of claim 1, wherein the low pass filter has a cut-off frequency lying between approximately one and four times a reciprocal of a mean period of a signal appearing at an output of the divider stage.

4. The system of claim 1, wherein at least two dissonant signals are applied to said control input of each tone generator.
